WILLIAM A. SMITH, OF PHILLIPSBURG, NEW JERSEY, ASSIGNOR TO INGERSOLL-RAND COMPANY, OF JERSEY CITY, NEW JERSEY, A CORPORATION OF NEW JERSEY.

ROCK DRILL.

1,414,225.

Specification of Letters Patent. Patented Apr. 25, 1922.

Application filed August 13, 1920. Serial No. 403,352.

To all whom it may concern:

Be it known that I, WILLIAM A. SMITH, a citizen of the United States, and a resident of Phillipsburg, county of Warren and State 5 of New Jersey, have invented certain new and useful Improvements in Rock Drills, of which the following is a specification.

This invention relates to fluid actuated rock drills of the hammer type, but more 10 particularly to a machine having a double ended differential reversible piston operated in a cylinder provided with a fluctuating pressure chamber at the rear of the rearwardly extending piston shank. Fluid pressure 15 sure is intermittently supplied to and exhausted from the main bore of the cylinder in front of and behind the main piston head and the primary objects of the present invention are to secure a long back travel for 20 the piston and a late cut-off on the forward stroke, thus producing a long admission of fluid pressure against the rear or forwardly driving pressure surface of the main piston head. I accomplish these and other desirable 25 objects primarily by means of a valve and a forward admission port and another admission port rearward of said forward admission port, for supplying fluid pressure behind the main piston head, communication 30 between the forward and rearward admission passages leading to said ports being controlled by said valve.

To all of these ends the invention consists of the combinations of elements and arrangement of parts hereinafter fully described and claimed and shown in the accompanying drawings, in which—

Figures 1 and 2 are diagrammatic longitudinal sectional elevations of a rock drill 40 embodying the invention showing the piston hammer in two different positions.

Referring to the drawings, A represents the cylinder of a rock drill having the chuck B through which the drill steel C is inserted 45 in the usual manner in position to receive the impact blows of the reversible reciprocating piston hammer which comprises the main piston head D having the forwardly and rearwardly extending shanks or extensions E and F formed with the reduced 50 necks G and H.

The main piston head D reciprocates within the larger bore J of the cylinder and the cylinder is provided with a back cylinder 55 portion or back head K having a bore L of

smaller diameter to receive the piston shank F. The forward portion of the cylinder is also provided with the reduced bore L' to receive the forward piston shank or extension E and the reduced bores L and L' in 60 this instance are the same diameter and the piston shanks E and F are of equal diameters so that the piston is reversible in the cylinder and may be turned end for end as desired in case the striking end becomes 65 chipped.

The cylinder A and the back head K are provided with a suitable arrangement of ports and passages partly controlled by the piston and partly controlled by a valve O for 70 distributing fluid pressure to different portions of the cylinder for actuating the piston.

Actuating fluid such as air under pressure is admitted at the inlet port P controlled by 75 the usual throttle valve Q. The chamber R at the rear of the back head K is under fluctuating pressure in accordance with this invention so that pressure is intermittently exerted on the pressure surface S of the rearwardly 80 extending piston shank F. The pressure is also intermittently supplied in front of and behind the main piston head D so that both the forwardly acting pressure surfaces of the piston and the rearwardly acting pressure surface of the piston are subject to intermittent pressure.

Fluid pressure is supplied to and exhausted from the fluctuating pressure chamber R in the back head by means of the passage T 90 leading from the said chamber R to a port U in the rear of the main cylinder bore, which port is controlled by the main piston head D. The cylinder is provided with the usual exhaust port V over-run by the piston 95 head in each direction of its travel.

The supply of fluid pressure to the rear end of the main cylinder bore J behind the main piston head D is controlled partly by the shoulder W of the piston shank F and partly by the valve O, and the manner in which this control is effected enables me to take advantage of the full power of a reversible piston having fluctuating or intermittent pressure on all of its operative pressure 105 surfaces.

As shown, a forward admission port *a* opens into the smaller rearward bore L of the cylinder casing and communicates with the valve chamber *b* of the valve O by means 110

of the forward admission passage *c*. Another rearward admission port *d* communicates with the valve chamber *b* by means of the rearward admission passage *e* and also 5 communicates with the inlet *P* by means of the passage *f*.

The valve *O* may be constructed in any suitable manner but in this instance is provided with the front head *g* and the rear 10 head *h* connected by a reduced neck *j* and the function of this valve is to control communication between the forward admission passage *c* and the rearward admission passage *e* in order to produce a late admission 15 of fluid pressure against the rear pressure surface of the main head *D* on the rearward stroke and prolong the admission. A reversible piston of the type shown thus has a longer back travel than is customary and has 20 a late cut-off on the forward stroke. The rear operative pressure surface *k* of the valve *O* is subject to fluctuating pressure through the passage *o*, in this instance connecting the forward end of the main cylinder bore *J* with 25 the rearward end of the valve chamber *b*. The forward operative pressure surface *p* of the valve *O* is subject to pressure through the passage *q* leading to the rearward end of the main cylinder bore. The valve is thus operated or thrown from one position to the 30 other as indicated in the drawings, in accordance with the movements of the piston.

Fluid pressure is supplied to the forward end of the main cylinder bore *J* through the 35 passages *r* and *s* which connect the annular groove *t* in the back head with the front end of the cylinder at the port *u*. The groove *t* communicates with the rearward admission port *d* and the forward port *u* for the front 40 end of the cylinder is controlled by the piston shank *E* and opens into the smaller forward bore *L'* as shown.

In the operation of the machine, let it be assumed that the piston is at the forward end 45 of its stroke and is about to start on the back stroke as indicated in Figure 1. The cylinder is shown exhausting through the exhaust port *V* and pressure is also exhausted from the front of the valve *O* through the passage 50 *g*. The live pressure on the rear surface *k* of the valve *O* has caused the valve to throw over or move to its forward position as indicated in Figure 1, closing communication between the forward and rearward admission 55 passages *c* and *e*.

The piston is ready for the rearward stroke by the admission of fluid under pressure to the front end of the cylinder through the passages *r* and *s* which are open to the 60 supply as shown in Figure 1. As the piston travels back, the exhaust port *V* to the back of the main head *D* is closed and the admission port *u* to the forward end of the cylinder is closed, but the shoulder *W* at the neck 65 of the rearwardly extending piston shank

over-runs the forward admission port *a*, without admitting pressure to the rear surface of the main head *D* because the forward admission passage *c* is still closed by the valve *O*. 70

After the main head *D* over-runs the cylinder exhaust port *V* the exhaust from the forward end of the cylinder is open as indicated in Figure 2, which also opens the rear end *k* of the valve *O* to exhaust through the passage *o* leading to the front end of the cylinder. The shoulder *W* on the neck of the rearward piston extension *F* then over-runs the rearward admission port *d* which admits pressure past the piston neck *H* to 80 the rear of the larger bore *J* of the cylinder, and also through the passage *q* to the front end *p* of the valve *O*, which throws the valve to its rear position indicated in Figure 2, thus opening communication between 85 the forward and rearward admission passages *c* and *e* and supplying full pressure behind the main head *D* to drive the piston forward. 90

Owing to the fact that no pressure is supplied to the rear of the main cylinder head *D* when the forward admission port *a* is uncovered by the piston shoulder *W*, the piston has a substantially long rearward stroke before the forward and rearward admission passages *c* and *e* are placed in communication by the action of the valve *O*, and on the other hand, the piston is given a late cut-off on the forward stroke because cut-off does not take place when the 100 rearward admission port *d* is over-run by the shoulder *W* but is delayed until the forward admission port *a* is over-run by the piston as indicated in Figure 1. 95

I claim:

1. In a fluid operated rock drill of the hammer type, the combination of a cylinder and reversible differential piston subject to fluctuating pressure on one of its forwardly acting pressure surfaces, means controlled by the piston for supplying motive fluid to the rearwardly acting pressure surface of the piston, a forward admission port and another admission port rearward of said forward admission port for supplying motive fluid to the other forwardly acting pressure surface of the piston, and a fluid actuated valve for controlling communication between forward and rearward admission passages leading to said forward and rearward admission ports. 105

2. In a fluid operated rock drill of the hammer type, the combination of a cylinder and reversible differential piston subject to fluctuating pressure on one of its forwardly acting pressure surfaces, means controlled by the piston for supplying motive fluid to the rearwardly acting pressure surface of the piston, a forward admission port and another admission port rearward of said 110

forward admission port for supplying motive fluid to the other forwardly acting pressure surface of the piston, and a fluid actuated valve subject to fluctuating pressure on opposed operative surfaces for controlling communication between forward and rearward admission passages leading to said forward and rearward admission ports.

3. In a fluid operated rock drill of the hammer type, the combination of a cylinder and a reversible piston, means controlled by the piston for supplying motive fluid to the forward end of the cylinder, a forward admission port and another admission port rearward of said forward admission port for supplying motive fluid to the rearward end of the cylinder, and a fluid actuated valve for controlling communication between forward and rearward admission passages leading to said forward and rearward admission ports, one operative surface of said valve being subject to the fluctuating pressure in the rearward portion of the cylinder behind the piston head, and another opposed operative surface of said valve being subject to the fluctuating pressure in the front portion of the cylinder, in front of the piston head.

4. In a fluid operated rock drill of the

hammer type, the combination of a cylinder 30 and reversible differential piston subject to fluctuating pressure on one of its forwardly acting pressure surfaces, means controlled by the piston for supplying motive fluid to the rearwardly acting pressure surface of 35 the piston, a forward admission port and another admission port rearward of said forward admission port for supplying motive fluid to the other forwardly acting pressure surfaces of the piston, and a fluid actuated valve for controlling communication 40 between forward and rearward admission passages leading to said forward and rearward admission ports, one operative surface of said valve tending to open communication 45 between said forward and rearward admission ports, being subject to the fluctuating pressure in the cylinder behind the main piston head, and another opposed operative surface of said valve being subject to the 50 fluctuating pressure in the cylinder in front of the main piston head tending to close communication between said forward and rearward admission ports.

In testimony whereof I have signed this 55 specification.

WILLIAM A. SMITH.
